UNITED STATES PATENT OFFICE.

GEORGE BROWNING, OF WILMETTE, ILLINOIS, ASSIGNOR TO CHICAGO FLEXIBLE SHAFT COMPANY, OF CHICAGO, ILLINOIS, A CORPORATION OF ILLINOIS.

ELECTRIC IRON.

Application filed August 15, 1925. Serial No. 50,368.

The purpose of this invention is to provide an improved construction in an electric iron with the particular purpose of affording in one implement a relatively large and 5 a relatively small iron deriving heat from one heating unit. It consists in the elements and features of construction shown and described as indicated in the claims.

This invention is designed to provide a 10 construction amounting to two irons in one, the smaller iron being adapted to be used apart from the electrical heating means, and, if desired, to be otherwise heated, the main part from which the smaller iron is thus 15 separable constituting an electric stove on which said smaller iron may be lodged for heating in the momentary,—or longer,—intervals of use, said smaller iron constituting a part of the larger one when it is thus 20 lodged and secured, and affording by its own handle the handle for the larger iron of which it is thus a part.

In the drawings:

Figure 1 is a plan view of the entire device including the smaller iron locked in plate on the base member to constitute the complete larger iron.

Figure 2 is a side elevation of the same.

Figure 3 is a partly sectional side elevation section being in a middle longitudinal vertical plane.

Figure 4 is a side elevation showing the plug socket tilted back releasing the smaller iron which is shown partly lifted off the base.

Figure 5 is a top plan of the base member which has the operating face of the larger iron, the smaller iron and the plug socket being removed.

Figure 6 is a section at the line 6—6 on Figure 5.

Figure 7 is a section at the line 7—7 on Figure 5.

Figure 8 is a forward side elevation of 45 the plug socket member.

Figure 9 is a partly sectional upper end view of the same as at the plane indicated by the line 9—9 on Figure 2.

Figure 10 is a section at the line 10—10 50 on Figure 2.

Figure 11 is a top plan view of the heating member removed from the base.

Figure 12 is a section at the line 12—12 55 on Figure 11.

Figure 13 is a detail section at the line 55 13—13 on Figure 11.

Figure 14 is an enlarged detail part of the section shown in Figure 3.

The implement comprises, as above indicated, a base member which has the smoothing face of the larger iron. This base member, 1, is integral as to a lower or base portion, 1^a, and an upper or flange portion, 1^b, which are separated by a horizontal slot, 3, which is milled in the original casting, extending across the front, as seen at 3^a, and along both sides, leaving standing connected the base portion and the flange, a neck, 1^c, formed hollow with an upwardly open cavity, 1^d, for lightening the member. At 70 the rear end or heel of the base it is rabbed at the upper side, as seen at 4^a, the rabbet extending down to the plane of the lower side of the slot, 3, and being about three-quarters of an inch wide. This rabbet 75 serves for mounting the heel bar, 10, to which the plug socket member, 11, is hinged, as hereinafter more particularly described.

The heating element comprises a sheet metal mount or support, 4, on which is 80 lodged the heating element proper consisting of a high resistance coil, 5, and the enclosing mica sheets, 6, 6. The sheet metal mount, 4, is shaped to conform substantially to the contour of the slot, 3, as to the front and side portions thereof, being thereby fork-shaped or U-shaped, and adapted when the mica-enclosed coils are lodged upon it, to be inserted from the forward end of the iron into the slot, 3, its two wings or 90 branches passing down alongside the neck, 1^c, and extending onto the horizontal face of the rabbet, as seen at 4^b. This sheet metal mount, 4, has a marginal flange, 4^a, of suitable width to guard the edge of the heating element and close the slot, 3, when the heating member as a whole is slid into place in said slot.

Beside this narrow marginal flange the sheet 4, has a short upstanding part 4^b extending over the toe of the smaller iron, 20, when the latter is lodged on the upper surface of the base member, as seen in several figures of the drawings.

The plug socket member, 11, is shown as 105 a casting (though it may be formed otherwise) which is hinged to the heel bar, 10, by lugs, 11^a, 11^b, of said plug socket member ex-

2

tending through openings, 10^b, in the heel bar which has an upwardly protruding boss, 10^c, extending its entire length, except as partly interrupted by the apertures mentioned and which is bored and threaded at the opposite ends to receive pintle screws, 13, 13, which are screwed into said opposite ends of the boss and engage the pivot lugs, 11^a, of the plug socket member. The socket 5 has insulatingly mounted, as indicated by mica disk, 15, and mica strip, 15^a, in the bottom of the cavity, 11^b, which receives the insulating plug terminal of the circuit core, the contact pins, 13, 13, from whose lower 10 ends inside the lugs 11^a, contact terminals, 14, 14, extend rearward and downward being guarded from short-circuiting contact with the metal of the socket member at the back side thereof by a mica strip, 15^a, which 15 is extended between said terminals and the back web of the socket member, and at the forward side by a mica member, 15, which is held in place under the heel bar, 10, by which 20 it is clamped onto the rear end portions of the top mica sheet of the heating element and onto the otherwise exposed portion just back of the reflexed end portion, 17^a, of the contact terminals, 17, 17, of the heating coil, said ends being exposed for contact 25 with the terminals, 14, 14. The heating coil is provided with these terminals, 17, 17, which protrude from between the enclosing mica sheets and are reflexed over the end of the upper one in order to expose said terminals under the terminals, 14, 14, as stated, the latter terminals being formed as substantially cylindrical knobs co-axial with the hinge pivot of the socket members whose access in the boss, 10^c, is a little distance above 30 the plane of the protruding coil terminals, 17, 17, so that the reacting of the plug socket member about its hinge pivot, does not disturb the contact of said knob terminals with the terminals, 17, 17, of the heating coil.

40 45 The slight crevice between the hinge boss, 10^c, of the heel bar, 10, and the foot of the socket member, 11, is guarded by the metal strip, 15^a to prevent intrusion of anything into touch with the terminals, 14, 14, which 50 might short circuit the current. For similarly guarding the terminals at the forward side of the plug socket member, the heel bar, 10, has a flange, 19, curved about the hinge pivot axis and with which, therefore, 55 the forward lower side of the plug socket member, 11, maintains contact or close approximation throughout the rocking of the socket member about its hinge connection, while the flange, 11, screens the contact terminals against any short circuiting contact.

60 65 The smaller iron, 20, is complete in itself for the function of a smoothing iron, having a handle, 21; detachably secured by screws, 22, 22. The toe of the small iron is

adapted to engage as described above, under the hood, 4^d, at the toe of the base member; and for locking it to the base member at the rear end, the plug socket has a forwardly projecting latch or the like, 20, which engages with the lower marginal edge of an aperture, 23^a, in the rear stem, 23, of the handle when the plug socket member is rocked forwardly about its hinge pivot; and said plug socket member has forwardly projecting spring fingers, 11^b, between which the rear post, 23, of the handle, 21, of the smaller iron is engaged when the plug socket is swung forward to engage the latch, 20, with the handle stem as described. 70 75 80

For convenience in this operation the plug socket has a handle lug, 25, provided with a non-metallic knob, 25^a,—wood or fibre; and a release lever, 26, pivoted on the post, 23, and extending against the plug socket between the spring fingers, 11^b, serves for conveniently disengaging the spring fingers from the handle of the smaller iron. 85

From the foregoing description, it may be understood that when it is desired to employ a relatively heavy and relatively broad-faced iron, as in ironing large and smooth articles, commonly called in laundry phraseology “flat work”—the small iron will be locked in place on the base member and will thereby become the handle means for operating the implement as a whole, and that the small iron will become heated and contribute not only its weight and the service of a handle, but also will constitute a 90 95 100 heat reservoir causing the instrument as a whole to hold the heat longer and be thereby adapted for the service of smoothing large moist areas, over which the iron may be manipulated rapidly without lowering its 105 temperature more rapidly than it can be replenished by the heating coil. But when the operator passes from flat work to the small and more or less complex articles, as 110 lingerie, ruffled and tripped garments which require frequent setting down of the iron to manipulate the fabric for giving the iron access to the intricacies of the garment, the smaller iron will be disengaged from the base which, resting on a suitable stand, serves as 115 a heating stove on which the smaller iron would be set down in each movement or longer interval of use required for adjusting the goods; and thus in the intervals the smaller iron will have restored the heat lost in the 120 alternate intervals of use.

It will be seen, therefore, that this invention provides two tools in one, adapted respectively, for the different sorts and conditions of laundry work arising in an ordinary varied assortment of articles constituting the ordinary “family wash”. 125

I claim:—

1. An electric laundry iron and the like having a base member with the smoothing 130

- face comprising integrally an upper and a lower portion, said base member being slotted edgewise parallel to the smoothing face inward from the front end, and from 5 the opposite longitudinal sides forming between said upper and lower portions a horizontally extending pocket for the electric heating element, in combination with said element inserted edgewise into said pocket, 10 and means for securing it therein.
2. In the construction defined in claim 1, foregoing, the heating element comprising a sheet metal support and mica-clad resistance coils lodged on said support, the margin of 15 the sheet metal support being flanged for enclosing the heating coils and closing the mouth of the slot in the base member, wherein the heating member is inserted.
3. In the construction defined in claim 1, 20 foregoing, the heating element comprising a sheet metal support and metal-clad resistance coils lodged on said support, the support having an up-turned flange extending up past the forward end of the part of the 25 base member above the edge slot therein, and reflexed inwardly thereabove to constitute an engagement for a handle means.
4. In a structure as defined in claim 1, the base member being flat on top, a handle 30 means in the form of a complete independently usable iron dimensioned for seating on the flat top of the base member, the heating element having a flange extending up outside the part of the base member above 35 the slot past the thickness of said part and in-turned for engaging the toe of the iron which constitutes the handle means.
5. In combination with the construction 40 defined in claim 1, foregoing, a handle member in the form of a complete independently usable iron dimensioned for seating upon the top of the base member, the latter having means at the toe end for engaging the toe 45 of said handle iron; a member hinged to the rear end of the base member; insulated contact terminals for the heating coils carried 50 by said hinged member, the latter having means at its forward side for engaging the rear end of the handle iron when said 55 hinged member is swung up toward the handle iron and adapted to release the latter when swung back therefrom, said hinged member having means releasably engaging the handle of the handle iron to hold said hinged member at the first mentioned engaged position.
6. An electric iron comprising a bottom 60 member having the bottom working face of the iron, and having enclosed in it an electric heating element, and comprising a complete 65 separably usable iron with a handle and smoothing body, said separable iron being detachably mounted on the bottom member for being heated thereby, and af-
- fording handle means for the combined members; the bottom member comprising at the heel end thereof a plug socket member hinged to the heel end and at the toe end means for engaging the toe of the separable iron; the latter and the hinged plug socket 70 member having co-operating features relatively positioned for engagement when the hinged member is swung up to working position for holding the separable iron securely on the bottom member. 75
7. An electric iron comprising a bottom member having the bottom working face of the iron, and having enclosed in it an electric heating element, and comprising a complete 80 separably usable iron with a handle and smoothing body, said separable iron being detachably mounted on the bottom member for being heated thereby, and af-
- fording handle means for the combined members; the bottom member comprising at 85 the heel end thereof a plug socket member hinged to the heel end and at the toe end means for engaging the toe of the separable iron; the latter and the hinged plug socket 90 member having co-operating features relatively positioned for engagement when the hinged member is swung up to working position for holding the separable iron securely on the bottom member, said engaging means comprising a spring catch carried by the 95 hinged plug socket member adapted to automatically engage the rear stem of the handle of the removable iron, and disengaging means also by said hinged part movable thereon for crowding against the handle 100 stem to forcibly release the hinged part from the handle.
8. An electric iron comprising a bottom member having the bottom working face of the iron, and having enclosed in it an electric 105 heating element, and comprising a complete separably usable iron with a handle and smoothing body, said separable iron being detachably mounted on the bottom member for being heated thereby, and af-
- fording handle means for the combined members; the bottom member comprising at the heel end thereof a plug socket member hinged thereto for releasably engaging the heel end of the separable iron, the heating 110 element in the bottom member having circuit terminals exposed upwardly under the hinge pivot line of said hinged plug socket member, the contact pins of the plug socket comprising substantially cylindrical enlargements axially aligned with the hinge pivot 115 and diametered for contact with said heating element terminals respectively throughout the range of the hinge movement. 120
- In testimony whereof, I have hereunto set 125 my hand at Chicago, Illinois, this 27th day of July, 1925.
- GEORGE BROWNING.
